SEPARATION OF THIOPHENOLS FROM
HYDROPHOBIC LIQUID MIXTURES

George W. Ayers, Jr., and Meyer S. Agruss, Chicago, and Richmond T. Bell, Deerfield, Ill., assignors to The Pure Oil Company, Chicago, Ill., a corporation of Ohio

No Drawing. Application June 21, 1941,
Serial No. 399,228

6 Claims. (Cl. 260—609)

This invention relates to a method for separating thiophenols from hydrophobic liquid mixtures containing the same and is more particularly concerned with a method for separating thiophenols from acid oils.

Mixtures of thiophenols, phenols and other oil-soluble weakly acidic organic compounds obtained from hydrocarbon oils by extraction with caustic alkali, are generally called "acid oils." Acid oils may contain substantial quantities of thiophenols, as well as alkyl phenols and other organic acidic compounds such as naphthenic acids and in some cases varying amounts of polycyclic aromatic ring phenolic compounds. The amount of thiophenols present in a specific acid oil is dependent upon the composition of the original hydrocarbon oil and the treatment to which the oil has been subjected. The acid oils are usually obtained by extracting cracked mineral oil distillates with strong aqueous alkali metal hydroxide solutions and the acid oils separated from the resulting extract by springing with suitable acidic material. Springing may be effected by adding sufficient acidic material to the aqueous alkali solution to neutralize the same. Acid oils as thus prepared ordinarily contain undesirable alkyl mercaptans. Acid oils substantially free of alkyl mercaptans may be readily obtained by steam stripping or boiling the aqueous alkali solutions prior to the springing operation.

Thiophenols in acid oils have been separated from alkyl phenols in the past by extracting the acid oils with an organic water insoluble solvent for alkyl phenols in the presence of aqueous solution of an alkali metal hydroxide in an amount approximately equivalent to the thiophenol content of the acid oil. Under such conditions alkyl phenols preferentially dissolve in the solvent. This method, however, does not produce substantially pure thiophenols.

It has now been discovered that substantially pure thiophenol fractions and substantially pure thiophenol compounds may be separated from acid oils which are substantially free of alkyl mercaptans by precipitation with heavy metal salts.

It is an object of this invention to recover thiophenols from acid oils in a substantially pure form.

It is another object of this invention to recover thiophenols substantially free of other weakly acidic organic compounds and free of

each other from acid oils which are substantially free of alkyl mercaptans.

It is still a further object of this invention to efficiently separate thiophenols from acid oils.

5 Other objects and advantages will be apparent from the following more detailed description.

As previously indicated, it has been found that thiophenols may be separated from acid oils that are substantially free of alkyl mercaptans in

10 a relatively pure state by precipitation with heavy metal salts such as salts of the heavy metals of Groups 1, 2 and 4 of the periodic table. In order to avoid contamination with alkyl mercaptans, such materials are removed from the

15 aqueous alkaline solutions which have been employed to extract the acid oils from hydrocarbon oils, preferably by steaming and/or boiling. Those alkaline solutions which have been used a plurality of times for the extraction of petroleum

20 oils and regenerated by steam stripping are preferred since these solutions ordinarily contain relatively high proportions of thiophenols. When heavy metal salts are added to acid oils obtained from such alkali solutions, heavy metal salts of

25 thiophenols are formed and these salts precipitate in a relatively pure form. This may be effected by simply agitating the acid oils with aqueous solutions or suspensions of appropriate heavy metal salts, preferably aqueous solutions

30 of salts of those heavy metals that are precipitated from acidic solutions with hydrogen sulfide. Heavy metal salts which have been found suitable for this purpose include water soluble salts of mercury, silver and lead. Particularly good 35 results have been obtained with water soluble salts of mercury. Suitable salts include mercuric cyanide, mercuric acetate, silver acetate, silver nitrate and lead acetate.

After precipitation of the heavy metal salts of 40 the thiophenols from the acid oil, the salts are separated therefrom by filtration or other appropriate means. These salts may be further purified by fractional crystallization from an appropriate solvent such as aqueous alcohol solution.

45 Thiophenols are then recovered from the heavy metal salts thereof by dispersing, i. e., suspending or dissolving the heavy metal thiophenolic salts in a suitable liquid such as a low boiling hydrocarbon liquid and acidifying the liquid as for example, by passing hydrogen sulfide therethrough, which frees the thiophenols.

Other acidifying agents can be used but best results are obtained by the use of an acid reagent 50 which precipitates the heavy metal in the form

of an oil insoluble salt. If the heavy metal phenolic salts have been suspended in an aqueous liquid, the thiophenols will separate as an oily layer and may be completely separated from the aqueous layer by decantation. If a non-aqueous liquid has been used such as low boiling petroleum hydrocarbons, the thiophenols dissolve in the liquid upon being acidified by the hydrogen sulfide. In this case the thiophenols may be subsequently separated from the petroleum hydrocarbon solvent by distillation. Individual thiophenols may be separated from each other in the same or a subsequent distillation by careful fractionation by virtue of difference in boiling point. It is, of course, apparent that the original acid oils may be fractionated prior to the precipitation therefrom of the heavy metal salts of thiophenols. In this way the phenolic heavy metal salts may be directly precipitated as substantially pure individual thiophenol compounds.

In a specific example, acid oil obtained by aqueous alkali extraction of a mixture of cracked and straight run Van Zandt and Schuler gasolines was separated from the alkali extracting solution by acidification and decantation. A portion of the acid oil was contacted with an equal volume of 10% aqueous mercuric cyanide solution and the white precipitate of mercuric aromatic mercaptide separated by decantation and washed with water. The washed precipitate was crystallized repeatedly from hot 80% aqueous ethyl alcohol solution by simply cooling the solution. The resulting material was identified as substantially pure mercuric o-tolyl mercaptide. This material constituted more than half of the original mercaptide precipitated. The purified white mercuric o-tolyl mercaptide was suspended in heptane and hydrogen sulfide gas passed through the suspension until precipitation of black mercuric sulfide was complete. This acidifies the thiophenol salts and frees the aromatic mercaptan which dissolves in the heptane. After washing with water, the aromatic mercaptan-heptane solution layer was distilled and o-thiocresol recovered as a residue.

In another example, a separate portion of the same acid oil was fractionally distilled and a fraction obtained, the boiling range of which was close to the boiling point of o-thiocresol. O-thiocresol boils at 194° C. and the boiling range of this fraction was 174° C. to 214° C. This narrow boiling fraction of the acid oil was treated with an aqueous solution of mercuric cyanide to precipitate mercuric aromatic mercaptide in a manner similar to that described in connection with the treatment of the first portion of acid oil. The precipitate was suspended in heptane, hydrogen sulfide passed through the suspension to precipitate mercuric sulfide and to free the aromatic mercaptan. The heptane solution of aromatic mercaptide was then distilled to remove heptane. The residue from the distillation of the heptane layer was fractionally distilled, yielding substantially pure o-thiocresol.

The fractional crystallization steps which were carried out in the aforementioned procedures may be reduced in number or eliminated by employing sufficiently sharp fractionation of the acid oil prior to the precipitation of the heavy metal salt.

While salts of thiophenols may be precipitated by the use of salts of metals other than those specified herein, it has been found that it is only by the use of salts of the metals herein disclosed

that the precipitates formed are of uniform composition and are simple salts of individual thiophenols which are readily purified as contrasted to precipitates obtained with other heavy metals which are complex mixtures of various thiophenol salts. It is exceedingly difficult to obtain substantially pure thiophenols from the latter precipitates.

The substantially pure thiophenols may be employed as solubility promoters in aqueous alkali metal hydroxide solutions for enhancing the ability of such solutions to extract mercaptans from petroleum oils. Pure thiophenols are also useful as additives for enhancing the lubricating properties of mineral lubricating oil and may also be employed as odorizing agents for natural gas. In general, the purified thiophenols may be employed instead of the corresponding hydroxy benzenes in many organic syntheses for the preparation of sulfur containing compounds whereby sulfur from the sulphydryl group, instead of oxygen from the hydroxy group, is present in the final product.

The foregoing general description of the invention and the specific examples described are sufficient to enable one skilled in the art to appreciate its value. The invention is not limited to the specific examples disclosed but is to be interpreted as broadly as the prior art permits in view of the following claims.

What is claimed is:

1. The process of separating substantially pure thiophenols from "acid oils" containing the same which are substantially free of alkyl mercaptans comprising contacting the "acid oils" with water-soluble salts of metals selected from the group consisting of mercury, lead and silver whereby to precipitate metal salts of thiophenols, separating said precipitated salts, dispersing the separated salts in a hydrocarbon liquid boiling below the boiling point of thiophenol, treating the dispersed salts with sufficient hydrogen sulfide to convert dispersed salts to an oily layer of substantially pure thiophenols dissolved in the hydrocarbon liquid and to precipitate metal sulfide and separating substantially pure thiophenols from the hydrocarbon liquid by fractionation.

2. Process in accordance with claim 1 in which the acid oils are fractionated prior to contacting with the water-soluble salt to separate a narrow boiling fraction approximating the boiling point of the pure thiophenol to be obtained.

3. The process of preparing a substantially pure thiophenol from acid oils containing the same which are substantially free of alkyl mercaptans comprising fractionating the acid oils to obtain a narrow boiling fraction which boils somewhat above and somewhat below the boiling point of the pure thiophenol, contacting the narrow boiling fraction with water soluble salt of mercury whereby to precipitate mercury-thiophenol compound, separating said precipitated compound, dispersing the separated compound in a hydrocarbon liquid boiling below the boiling point of the thiophenol, acidifying the dispersion with hydrogen sulfide to precipitate mercury-sulfide and to free thiophenol as a solution in said hydrocarbon liquid and separating the thiophenol from the hydrocarbon liquid.

4. Process in accordance with claim 3 in which the substantially pure thiophenol is o-thiocresol and the narrow boiling fraction boils from about 174° C. to 214° C.

5. Process in accordance with claim 1 in which the precipitated salts are purified by functional

crystallization from a hot aqueous alcohol solution prior to dispersing the salts in said hydrocarbon liquid.

6. The method of obtaining substantially pure thiophenols from acid oil substantially free of alkyl mercaptans and containing phenols and thiophenols which comprises contacting said acid oil with an aqueous solution of a mercury salt in sufficient quantity to precipitate the thiophenols as mercury salts, separating the precipitate from the liquid and washing it with water, purifying the precipitate by dissolving it in hot

5 aqueous alcohol solution and crystallizing the dissolved salts therefrom by cooling the solution, suspending the crystallized salts in a low boiling hydrocarbon liquid from which thiophenols can be readily separated, contacting the suspension with hydrogen sulfide until precipitation of mercury as sulfide is complete and separating the liberated thiophenols from the dispersing liquid.
